[57] **CLAIM**

The ornamental design for a wall plate for electrical wiring device, as shown and described.

DESCRIPTION

FIG. 1 is a perspective view of a wall plate for electrical wiring device showing our new design;

FIG. 2 is an enlarged front elevational view thereof;

FIG. 3 is an enlarged right side elevational view thereof;

FIG. 4 is an enlarged rear elevational view thereof;

FIG. 5 is an enlarged top plan view thereof;

FIG. 6 is an enlarged bottom plan view thereof;

FIG. 7 is a perspective view of a second embodiment of the design of FIG. 1;

FIG. 8 is an enlarged front elevational view of FIG. 7;

FIG. 9 is an enlarged right side elevational view of FIG. 7;

FIG. 10 is an enlarged rear elevational view of FIG. 7;

FIG. 11 is an enlarged top plan view of FIG. 7; and,

FIG. 12 is an enlarged bottom plan view of FIG. 7.

FIG. 1.

FIG. 5.

FIG. 6.

FIG. 2.

FIG. 3.

FIG. 4.

FIG. 7.

FIG. 8.

FIG. 9.

FIG. 11.

FIG. 12.

FIG. 10.
